(57) **CLAIM**

I claim the ornamental design for a receiver configuration for a bottling machine, as shown and described.

DESCRIPTION

FIG. 1 is a bottom perspective view of a receiver configuration for a bottling machine in accordance with an embodiment of my new design.

FIG. 2 is a top perspective view thereof.

FIG. 3 is a front elevation view thereof.

FIG. 4 is a left side elevation view thereof.

FIG. 5 is a top view thereof.

FIG. 6 is a bottom view thereof.

FIG. 7 is an exploded view thereof; and,

FIG. 8 is a cross-sectional view of the receiver configuration for a bottling machine taken along line 8-8 in FIG. 6.

The rear and right-side elevation views are omitted as they are mirror images of the front and left side elevation views, respectively.

The broken lines in the drawings depict unclaimed environmental subject matter.
